UNITED STATES PATENT OFFICE

2,219,281

CHIMNEY

Sigfrid Granstrom, North Bend, Oreg.

Application July 12, 1939, Serial No. 284,068

1 Claim. (Cl. 72—92)

The present invention relates to new and useful improvements in chimneys and has for its primary object to provide, in a manner as hereinafter set forth, a device of this character comprising a plurality of reinforced concrete sections of a novel construction and arrangement whereby the chimney may be expeditiously erected by unskilled labor and wherein the use of mortar is unnecessary.

Another very important object of the invention is to provide a sectional chimney of the aforementioned character which may be conveniently taken down when desired for removal to another location or for any other purpose.

Still another very important object of the invention is to provide a chimney of the character described which may expand and contract as the temperature varies without sustaining damage.

Other objects of the invention are to provide a chimney of the character set forth which will be comparatively simple in construction, strong, durable, fireproof, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is an elevational view of a chimney constructed in accordance with the present invention.

Figure 2 is a vertical sectional view, taken substantially on the line 2—2 of Fig. 1.

Figure 3 is a view in front elevation of the base.

Figure 4 is a view in side elevation of the base.

Figure 5 is a top plan view of the base.

Figure 6 is a view in front elevation of the lower section which is mounted on the base.

Figure 7 is a top plan view of the lower section.

Figure 8 is a bottom plan view of the lower section.

Figure 9 is a view in front elevation of an intermediate section which is to be used when a flue is to be connected to the chimney at an intermediate point.

Figure 10 is a view in side elevation of the section shown in Fig. 9.

Figure 11 is a top plan view of the section shown in Figs. 9 and 10.

Referring now to the drawings, in detail, it will be seen that the embodiment of the invention which has been illustrated comprises a substantially square concrete base which is designated

generally by the reference numeral 1. The base 1 includes an integral flue 2. Projecting laterally from the flue 2 is an integral conduit 3 for the reception of a stove pipe or the like. The base 1 has formed in its marginal portion a recess constituting a seat 4.

Mounted on the base 1 is a plurality of superimposed chimney sections 5. Each section 5 includes a cylindrical flue 6 which is vertically aligned with the flue 2 of the base 1. Each section 5 further includes an offset intermediate portion 7 depending from the flue 6 and merging into a substantially square outer wall 8.

The lower portion of each flue 6 has formed therein an internal seat 9 with which the upper end portion of the subjacent flue is engageable. Then, the upper portions of the outer walls 8 of the sections 5 have formed therein recesses constituting external seats 10 in which the lower end portions of the superjacent walls 8 are engageable. It will be noted that the lower end of the lowermost section 5 rests on the seat 4 of the base 1. It will also be noted that this lowermost section 5 has formed therein an opening 11 which is aligned with the flue conduit 3.

Mounted on the uppermost section 5 is a cap which is designated generally by the reference numeral 12. The upper portion of the cap 12 is externally tapered, as at 13. The lower end of the cap 12 engages the seat 10 of the uppermost section 5, as shown to advantage in Fig. 2 of the drawings. Also, the upper portion of the cap 12 has formed therein a seat 14 with which the upper end of the uppermost section 5 is engageable.

It is thought that the manner in which the chimney is erected and taken down will be readily apparent from a consideration of the foregoing. It may be well to here state that all of the members 1, 5 and 12 are preferably of concrete suitably reinforced, as at 15. As many of the sections 5 may be used as may be necessary to erect a chimney of any desired height. When the chimney has been erected the portions 6, 7 and 8 of the sections 5 define, in conjunction with each other, a plurality of annular air chambers or spaces 16 from substantially the bottom to the top of the chimney. The construction and arrangement is such that the chimney may be erected or taken down without the use of skilled labor.

In Figs. 9, 10 and 11 of the drawings there is illustrated an intermediate section 5 which is adapted for connection with a stovepipe or stack. Toward this end, the flue portion 6 of this sec-

tion 5 has formed integrally therewith and communicating therewith a conduit 17 which is substantially similar to the conduit 3. When the conduit or connection 17 is used a section similar 5 to the lowermost section 5 shown in Fig. 2 of the drawings and having the opening 11 therein is to be used.

It is believed that the many advantages of a sectional chimney constructed in accordance with 10 the present invention will be readily understood and although a preferred embodiment of said chimney is as illustrated and described, it is to be understood that changes in the details of construction and in the combination and arrangement 15 of parts may be resorted to which will fall within the scope of the invention as claimed.

What is claimed is:

A chimney comprising a base having a marginal recess therein constituting a seat, a circular flue integral with the base and rising therefrom, an integral conduit projecting laterally from the flue and communicating therewith, a substantially square chimney section mounted on the base in spaced relation to the flue and engaged in the seat, said chimney section having an opening therein aligned with the conduit for the reception 10 of a stovepipe for connecting said stovepipe to the chimney, said chimney section further including an integral flue portion resting on the upper end of the first named flue and aligned therewith.
